Philip J. Brownscombe, East Orange, N. J., and
Carl Kertesz, Long Island City, N. Y., assignors
to Universal Camera Corporation, New York,
N. Y., a corporation of Delaware

Application November 2, 1938, Serial No. 80,830

Term of patent 7 years

To all whom it may concern:

Be it known that Philip J. Brownscombe and
Carl Kertesz, both citizens of the United States
and residents, respectively, of East Orange, in
the county of Essex and State of New Jersey,
and of Long Island City in the county of Queens
and State of New York, have invented a new,
original, and ornamental Design for a Photo-
graphic Exposure Meter or Similar Article, of
which the following is a specification, reference
being had to the accompanying drawing, forming
part thereof, in which,

Fig. 1 is a top plan view of a photographic ex-
posure meter or similar article embodying our
design; and

Fig. 2 is an edge view thereof.

We claim:

The ornamental design for a photographic ex-
posure meter or similar article, substantially as
shown.
